UNITED STATES PATENT OFFICE.

PHILIP J. MARKMANN, OF ST. LOUIS, MISSOURI.

REINFORCEMENT FOR CONCRETE STRUCTURES.

Application filed March 2, 1925. Serial No. 12,558.

This invention relates generally to reinforcements for concrete structures, and particularly to combined steel and concrete construction for columns, or like structures, which in service are adapted to withstand great compressive stresses in a longitudinal direction.

The principal object of the invention is to greatly increase the strength of a bar reinforced concrete column of a given size over that which can be attained when bar reinforcements of the types in former and present practice are utilized, and the invention realizes its greatest advantage because of the fact that when it is necessary to provide a column capable of supporting a predetermined load, a column of the strength necessary to support the designated load may be constructed in accordance with my invention of a considerably smaller diameter than if said column were constructed as heretofore.

In the construction of office buildings, hotels and other large structures, the question of the loss of space due to the presence of many columns of relatively large diameters is an important one, and it is highly desirable to utilize columns which are as small as practicable. However, heretofore it has not been possible to reduce the diameters of bar reinforced concrete columns because of the physical limitation of the steel bar ratio with the former types of steel bar reinforcements, which natural limitation of the steel ratio means a corresponding forced limitation of the potential strength of the column. In the use of my improved reinforcement in connection with concrete columns the diameters of said columns are reduced to a minimum and much space which was formerly lost is thereby saved.

Briefly stated, my invention comprises the utilization of the ordinary bar reinforcement of the type comprising longitudinal bars and a helically arranged bar associated with said bars. This reinforcement is so arranged that it is located relatively close to the outer face of the column, and because of such location and of the cylindrical shape of said reinforcement there is a relatively large space within said reinforcement in which no reinforcing bars heretofore have been located. In carrying out my invention I arrange a second bar reinforcement within the space mentioned, and because of the presence of this second reinforcement the

strength of the column is materially increased.

I am aware that patents have been granted on reinforcements for concrete columns which comprise a reinforcement within a reinforcement, but these reinforcements have objectionable features in several respects. A disadvantage in connection with the reinforcements mentioned is due to the fact that the reinforcing elements are of such shape that the free flow of concrete within the form is interfered with. Another disadvantage is due to the fact that the inner and outer reinforcing elements of the reinforcements mentioned are in the form of units having comparatively large flat surfaces, and the adherence of the concrete to said surfaces is not as good as that of the concrete to bars. In my improved reinforcement both the outer and inner reinforcing members are composed of bars which are spaced apart from each other a sufficient distance to permit the free flow of concrete therebetween, and also the spaces between the form and the outer skeleton, between the outer and inner skeletons, and inside of the inner skeleton, allow unobstructed passage to the concrete poured into the form.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a fragmentary vertical section of a concrete column, or like structure, reinforced in accordance with my invention.

Fig. II is a cross section on the staggered line II-II of Fig. I.

Fig. III is a cross section on the staggered line III-III of Fig. I.

Fig. IV is an isometric view of a fragment of a concrete column reinforced in accordance with my invention.

In the drawing, A designates a concrete structure which comprises a footing B, the first floor slab C, a column D adapted to aid in the support of the first floor slab C, and a column E which is interposed between said first floor slab C and the next higher floor slab (not shown). Interposed between

the footing B and the lower end of the column D is a bed plate 1, said bed plate being adapted to support the entire stack of columns which extend from the top of said bed plate to the top of the structure. The bed plate 1 may be circular in plan, as shown in Fig. III, the particular bed plate illustrated in the drawing comprising horizontal top and bottom walls 2 and 3 and annular walls 4 and 5 connecting said top and bottom walls together. The bed plate 1 is also provided with an outer upstanding annular flange 6, and said bed plate is provided with sets of radial ribs 7 and 8 which, together with the aforementioned parts, give to the bed plate structure a form adapted to provide for the required strength to withstand the compressive, tensile and shearing stresses to which it is subjected. As shown by the drawing, the bed plate 1 is preferably cast, whereby the various parts of said bed plate are formed integral with each other. In use the cavities within the bed plate 1 are filled with concrete and a body of concrete, annular in shape, is built up outside of the wall 5, the side face of said body of concrete being flush with the outer face of the upstanding flange 6 and the top face of said body of concrete being flush with the upper face of the top wall 2 of the bed plate. 9 designates anchor rods which are embedded in the concrete footing B and pass through openings in the top and bottom walls 2 and 3 of the bed plate into the column D. It is apparent from the arrangement shown and described that a very substantial base is provided for the stack of columns, said base comprising the metallic bed plate combined with the concrete and the foundation anchors embedded in the footing below and the column above and passing through said bed plate.

F designates an outer reenforcing skeleton which comprises a plurality of bars G extended longitudinally of the structure and a helically arranged bar H which encircles said plurality of bars G and is secured thereto in any suitable manner. Reenforcing skeletons of the type to which the outer reenforcing skeleton F belongs are very well known and have been in common use for some time, and when said reenforcing skeletons are used in a structure of some height, for instance in a building having a number of floors, said skeletons are made in sections which are superimposed one above the other. When used as an element of my improved duplex reenforcement the longitudinal rods G of the reenforcing skeleton F rest upon the upper surface of the top wall 2 of the bed plate 1, as shown in Fig. I, and the upper end portions of said longitudinal rods, conforming to common practice, extend some distance above the top surface of the first floor slab C. The sections of the

outer skeleton F extend from the base of the stack of columns to the top thereof, one of said sections being usually associated with each individual column and the longitudinal rods of each of said sections being extended into the column above the column with which said longitudinal rods are associated (Fig. I). The lower ends of the longitudinal rods of the sections of the reenforcing skeletons F above the lowermost section rest upon the floor slabs of the building, as suggested by dotted lines in Fig. I, and it is therefore plain that because the upper end portions of the longitudinal rods of the lower section extend above the floor slab the upper end portions of the longitudinal rods of the lower section will overlap the lower end portions of the longitudinal rods of the section immediately above said lower section. This, however, is the usual construction, and it need not be described further, all that need be known being that the longitudinal rods of adjoining sections overlap each other in a manner to cause the stresses to be transmitted from the rods of the higher section to the rods of the lower section indirectly through the concrete by bond.

Located within the cylindrical outer reenforcing skeleton F is an inner reenforcing skeleton J which comprises a plurality of bars 10 extended longitudinally of the structure. As will appear later herein, the inner skeleton, like the outer skeleton, is made in sections which are superimposed one above the other, and the lower ends of the longitudinal rods of the lowermost section rest upon the upper surface of the top wall 2 of the bed plate 1. Considering the lowermost section of the inner skeleton J, it will be seen that the longitudinal bars 10 extend from the upper surface of the bed plate 1 to a point slightly above the top face of the first floor slab C. Associated with the longitudinal bars 10 is a plurality of spacing rings 11 and 12 in the form of annular members which encircle said longitudinal bars, as shown clearly in Figs. I, III and IV, said spacing rings being spaced apart from each other in a vertical direction as shown in Fig. I. The longitudinal bars and the spacing rings are secured together, and to effect this connection I employ U-bolts 13 which embrace the longitudinal bars 10 and have threaded end portions which are passed through apertures in said spacing rings and receive nuts 14. It is apparent from this that the elements which make up each section of the inner skeleton J are securely fixed together to produce a rigid unit which may be conveniently handled as a whole, and as such hoisted above the outer skeleton and lowered into the same into position. Secured to the upper face of the bed plate 1 is a member 13' having an upturned annular

flange 14'. The member 13' is so located on the bed plate 1 that when the longitudinal bars 10 of the lowermost section of the inner reenforcing skeleton J are arranged in a circle about the upturned flange 14' thereof and with the lower ends of said bars in contact with the outer face of said upturned flange, the lower end of said lowermost section of said reenforcing skeleton will be properly positioned with respect to the bed plate. In other words, the member 13' constitutes a means for properly locating the lower end of the inner skeleton J and also said member 13' prevents the lower end of said skeleton from being shifted by the concrete when it is poured into the form.

As has been stated herein, the upper end portions of the longitudinal bars 10 of each section of the inner skeleton J extend above the upper surface of the next floor slab above the column with which said section is associated, and instead of overlapping the end portions of the longitudinal bars of adjoining sections of the reenforcing skeleton J, as is done in connection with the outer skeleton F, I abut the ends of said longitudinal bars. In this way the compressive stresses are transmitted directly from the longitudinal bars of one section of the reenforcement J to the longitudinal bars of the next section of said reenforcement instead of through the concrete, as is the case with overlapped joints. To provide means for insuring actual bearing of one bar on another, I employ sleeves 15 (Figs. I and II), which encircle the adjoining ends of the bars and are of sufficient length to overlap said ends of said bars some distance, as shown in Fig. I. After the lower column D and the first floor slab C of the structure provided with my improved reenforcement has been poured and it is desired to arrange the second section of the inner reenforcing skeleton in place, the sleeves 15 are dropped over the upper end portions of the longitudinal bars of the lower section, which end portions extend above the upper surface of the floor slab C and are rigidly held thereby. The lower end portions of the longitudinal members of the second or upper section are then brought over the upper ends of the sleeves 15, and said bars are moved downwardly into said sleeves until said upper bars rest upon the top faces of the longitudinal bars of the lower section. In this way butt joints are made between the various upper longitudinal bars and the lower longitudinal bars of adjoining sections of the skeleton J, and the end portions of said bars are prevented from being displaced relative to each other by the sleeves 15. Connecting the lower ends of the longitudinal bars of the upper sections or the upper ends of the longitudinal bars of the lower sections as described also has the effect of properly locating the

lower end of each section in its proper central position. To provide for firm contact between the various longitudinal bars of the inner skeleton I provide the ends of said longitudinal bars with machined faces, and to provide firm contact between the longitudinal bars of the lowermost sections of the outer and inner skeletons with the bed plate 1 I provide the top wall 2 of said bed plate and the lower ends of said bars with machined faces.

In erecting a structure provided with my improved duplex reenforcement, the outer skeleton F is arranged in position in the usual way and the inner skeleton J is located within said outer skeleton, the upper end of said inner skeleton being temporarily held in its true central position by wires which extend to the form, or to the outer skeleton. After the form has been erected the concrete may be poured, and because of the arrangement of the skeletons and due to the fact that said skeletons are made up of properly spaced bars there will be nothing to interfere with the free passage of the concrete into the form and the free flow of concrete between and around all bars.

The utilization of a metallic bed plate with a reenforced concrete column of the type disclosed herein is a distinct improvement over the art, for the reason that said bed plate furnishes a bearing of sufficient strength to meet and resist the relatively high compressive stresses of any one or all of the longitudinal bars, square inch for square inch. It also furnishes a bearing for the whole compressive stress of the concrete body of the core area of the column. The intensity of this latter stress is only a fraction, say one-fifteenth, of the intensity of the stress transmitted by the bars, but these two greatly differing intensities in their travel through the bed plate are converted into a uniform vertical pressure upon the footing due to the compression-, tension- and shear-resisting strength of the bed plate.

In the case of a high ratio of longitudinal steel reenforcement, which by my invention may be easily and practically accomplished, the average stress over the gross core area of the column will exceed the allowable bearing pressure even upon a surface of concrete "at least twice the loaded area" (recommendations of joint committee and American Concrete Institute and special ruling of Chicago building department). Even the unit vertical compressive stress of the concrete of a column with a spiral reenforcement of $1\frac{1}{2}$ percent, for example, will exceed the allowable bearing pressure upon the concrete of the footing. The metallic bed plate is capable of receiving these pressures and of transmitting them to the upper surface of the footing as a uniform pressure of the allowable amount pro-

vided the bearing area of the bed plate is of corresponding size. The necessity of transmitting the column pressure to the footing, partly in bearing and partly by bond on stub bars placed in the footing, or by interposition of a cap block either of a richer mixture of concrete or spirally reinforced, together with stub bars which transmit the stress of the steel reinforcement, is entirely 10 eliminated by the use of the metallic bed plate 1 between the column and the footing. It is quite plain that the thickness of the footing depends only on the demands of bending and shear stresses developed in 15 spreading the column load from the base area of the bed plate over the required soil area in the case of a spread footing on soil, or over a group of piles, or over a caisson pier, as the case may be. As no stub bars of 20 the types formerly used are utilized in connection with my improved reinforcement, no special depth of the footing need be considered or provided.

The average strength of the gross core 25 area of a column is a function of the unit stress of the concrete either laterally free or restrained and of the longitudinal steel ratio. When the former is fixed, viz., concrete laterally free or restrained, the said average 30 strength becomes a function of the remaining variable, the longitudinal steel ratio, and said average strength increases as the said steel ratio increases to a maximum with the greatest practicable or theoretically permissible 35 steel ratio. Practical considerations allow a steel ratio fully as high, and even higher, than that fixed by the Chicago building code (p equals .08); for example, when the column is constructed with my duplex 40 bar reinforcement. Theoretical considerations would allow a steel ratio considerably higher than indicated as advisable by practical considerations of the sizes of the available chutes for dropping and placing the 45 concrete into the form so as to assure a complete saturation of the space surrounding the reinforcing skeletons. It would go beyond the scope of this application to demonstrate the theoretical limit of steel ratio. 50 Suffice it to say here, the theoretical limit is above the practical limit, and the limit of 8 percent fixed by the Chicago building code, for example, is not too high, rather not high enough. The reinforcing system in use 55 heretofore has simply not allowed even as much as a near approach to that ratio. My invention makes the approach to and even the passing of said steel ratio a matter of relatively simple and easy accomplishment.

60 I claim:—

1. A reinforcement for concrete structures comprising a reinforcing skeleton formed of bars, and a second reinforcing skeleton within the first mentioned skeleton, 65 said inner skeleton comprising bars extend-

ed longitudinally of the structure with which the reinforcement is associated, members for connecting said longitudinal bars together to produce a unit, and means removable with respect to said members 70 whereby each of said longitudinal bars is individually connected to said members, said means being in engagement with said longitudinal bars and with said members.

2. A reinforcement for concrete structures comprising a reinforcing skeleton formed of bars and a second reinforcing skeleton arranged within the first mentioned skeleton, said inner skeleton comprising bars 75 extended longitudinally of the structure with which the reinforcement is associated, annular members associated with said bars, and means supported by said annular members and independently adjustable with relation thereto whereby said bars and said 80 annular members are connected together.

3. A reinforcement for concrete structures comprising a reinforcing skeleton composed of bars extended longitudinally 85 of the structure with which the reinforcement is associated, and circular bars associated with said longitudinal bars, and a second reinforcing skeleton arranged within the first mentioned skeleton, said inner skeleton comprising bars extended longitudinally 90 of the structure with which the reinforcement is associated, annular members associated with said bars, and fastening devices supported by said annular members and independently adjustable with relation 95 thereto whereby said bars and said annular members are connected together.

4. A reinforcement for concrete structures comprising a reinforcing skeleton composed of bars extended longitudinally 100 of the structure with which the reinforcement is associated and spiral bars associated with said longitudinal bars, and a second reinforcing skeleton arranged within the first mentioned skeleton, said inner skeleton comprising bars extended longitudinally 105 of the structure with which the reinforcement is associated, annular members associated with said longitudinal bars, and U-bolts for connecting said longitudinal 110 bars to said annular members, said U-bolts being capable of independent movement relative to said annular members.

5. A reinforcement for concrete structures comprising a metallic base member on 115 which said concrete structure is supported, an outer reinforcing skeleton made in sections arranged one above the other supported by said base member, and a second reinforcing skeleton arranged within said 120 outer reinforcing skeleton and supported by said base member, said second reinforcing skeleton being made in sections arranged 125 one above the other.

6. A reinforcement for concrete struc- 130

tures comprising a bed plate on which said concrete structure is supported, a footing below said bed plate, an outer reenforcing skeleton supported by said bed plate, an inner reenforcing skeleton within said outer reenforcing skeleton and supported by said bed plate, and an anchor rod embedded in said footing and passed through said bed plate into said concrete structure.

10 7. A reenforcement for concrete structures comprising a metallic bed plate on which said concrete structure is supported, an outer reenforcing skeleton composed of bars extended longitudinally of the structure with which the reenforcement is associated and supported by said bed plate, and spiral bars associated with said longitudinal bars, a second reenforcing skeleton arranged within the first mentioned reenforc-

ing skeleton, said second mentioned reenforcing skeleton comprising bars extended longitudinally of the structure with which the reinforcement is associated and supported by said bed plate, annular members associated with said longitudinal bars, and fastening devices for connecting said longitudinal bars to said annular members, said inner skeleton being made in sections arranged in alinement with each other with ends of the longitudinal bars of one section abutting ends of the bars of an adjacent section, and sleeves arranged to encircle and overlap said abutting ends of said longitudinal bars.

In testimony that I claim the foregoing I 35
hereunto affix my signature.

PHILIP J. MARKMANN.
